UNITED STATES PATENT OFFICE

97,636

DESIGN FOR LACE

Bert Edson, Pawtucket, R. I.

Application October 22, 1935, Serial No. 59,169

Term of patent 3½ years

To all whom it may concern:

Be it known I, Bert Edson, a citizen of the United States of America, residing in Pawtucket, county of Providence, and State of Rhode Island, have invented a new, original, and ornamental Design for Lace, of which the following is a specification, reference being had to the accompanying drawing, forming part thereof, wherein,

The figure is a plan view of a piece of lace showing my new design.

I claim:

The ornamental design for lace, substantially as shown.

BERT EDSON.
